UNITED STATES PATENT OFFICE

HERMAN SCHWARZE, OF BIRMINGHAM, MICHIGAN, ASSIGNOR TO GENERAL MOTORS CORPORATION, OF DETROIT, MICHIGAN, A CORPORATION OF DELAWARE

DISTRIBUTOR MOUNTING

Application filed November 7, 1927. Serial No. 231,754.

This invention relates to a distributor thereof opposite that on which the distributor is located, there is provided an oil pump 23 into which open intake and discharge conduits 24. The shaft 21, which carries the driving pinion 22 of the pump, is journaled in the bearing 19 and is keyed, as shown in the drawing, to the distributor shaft 18 so that the two shafts are positively connected for driving purposes and yet are capable of a certain amount of axial movement relative to each other without affecting the driving connection therebetween.

It is an object of this invention to provide a new and improved distributor mounting which will provide for accurate manual spark adjustment in addition to the full automatic adjustment provided in the distributor.

It is a further object of the invention to provide a distributor mounting of this character which will allow a slight amount of end play in the distributor shaft so that binding of the parts, and the consequent friction and overheating, will be avoided.

15 It is a further object of the invention to arrange the distributor shaft in such a way that the oil pump normally carried at the lower end of the distributor shaft may be placed outside of the crankcase and in an 20 accessible position.

Other objects and advantages of the invention will appear in the course of the following description, taken in connection with the accompanying drawing and appended 25 claims.

In the drawing:

Fig. 1 is an end view, with parts broken away and in section, of part of a conventional internal combustion engine in which 20 is embodied my invention.

Fig. 2 is a view on the line 2—2 of Fig. 1.

Fig. 3 is a plan view of the fastening plate shown in the preceding figures.

Fig. 4 is an exploded view, showing a part 25 of the engine, the clamping plate, and the pointer.

Referring to the drawing, I have illustrated in Fig. 1 an internal combustion engine comprising an engine block or casting 40 10 and cam shaft 12. The cam shaft 12 is provided with a worm gear 14 which meshes with pinion 16 fixed on the distributor shaft 18 by means of a pin 17 which extends through the shaft 18 and through apertures 45 in the sleeve portion 15 of pinion 16. Shaft 18, as shown in the drawing, is set at an angle to the vertical and is journaled at its lower end in a bearing 19 which is suitably secured in the engine block. On the 50 outside of the engine block, on the side

thereof opposite that on which the distributor is located, there is provided an oil pump 23 into which open intake and discharge conduits 24. The shaft 21, which carries the driving pinion 22 of the pump, is journaled in the bearing 19 and is keyed, as shown in the drawing, to the distributor shaft 18 so that the two shafts are positively connected for driving purposes and yet are capable of a certain amount of axial movement relative to each other without affecting the driving connection therebetween.

The upper portion of the distributor shaft is journaled in a housing 20 which extends through an aperture in the engine block. Surrounding the housing 20 just outside the engine block is a bifurcated plate or stamping 25 provided with bolt 26 for rigidly fixing the plate 25 to housing 20. Plate 25 is fixed to the engine block by means of set bolt 27. Set bolt 27 is provided between the head and threaded portion with a shoulder 28 which is slightly deeper than the thickness of plate 25. I prefer to make the parts of a thickness which will permit a thirty-second of an inch end play of the plate 25 and housing 20 relative to the engine block. A graduated scale 36 concentric with housing 20 is provided on the lower portion of plate 25.

Surrounding housing 20 just above the plate 25 is the pointer 32 which is provided with a longitudinally extending slot 33 connecting with the opening which is adapted to receive the housing 20. The pointer 32 comprises a stamping which is roughly of an inverted cup shape, or, in other words, is flanged downward about its periphery. Extending through the side flanges in the region of the slot 33 is a clamping bolt 34 by means of which the pointer can be clamped to housing 20. At its upper end the housing 20 carries the usual distributor mechanism 30 (not shown in detail).

The housing is set at the proper position 95 at the factory and no manual adjustment is ordinarily required. If such adjustment becomes necessary, however, bolt 26 may be loosened and the housing 20 and pointer 32 rotated the desired amount either direction. 100

The bolt 26 is then tightened to clamp the housing 20 firmly in position.

In assembling the parts at the factory, the distributor shaft 18 carrying the usual parts 5 of the distributor mechanism is inserted in the housing 20 from the upper end and the pinion 16 then keyed thereto. It may be noted that the upper end of the pinion sleeve 15 fits snugly against the lower end 10 of housing 20, thus permitting rotation but not longitudinal movement of the shaft and housing relative to each other. Plate 25 is then placed over the opening in the engine block and is fixed in position by means of 15 bolt 27. Pointer 32 is then fixed in its proper place on housing 20. Housing 20 is then inserted in the engine block and the lower end of shaft 18 pushed down into the housing 19 of the oil pump shaft. With the 20 pointer 32 abutting against plate 25, the bolt 26 is tightened, thus clamping plate 25 to housing 20. Since bolt 27 permits plate 25 a slight amount of play, this construction permits the housing 20 and distributor shaft 25 a slight amount of axial movement relative to the engine block. The lower side of pinion 16 is slightly spaced from the adjacent end of housing 19 for permitting this movement. The construction shown and 30 described holds the parts firmly yet permits a very slight axial movement of the parts. This arrangement prevents binding and overheating occasioned by unequal expansion and contraction or from any other cause. 35 The angular arrangement of the distributor shaft permits the location of the oil pump at the side of the engine in a position readily accessible to a mechanic.

I claim:

40 1. In an internal combustion engine, a distributor housing having an anchoring element fixed thereon mounted in said engine, a distributor shaft journaled in said housing and driven by said engine, and a non-rotatable connection between said anchoring element and engine capable of limited longitudinal movement.

2. In an internal combustion engine, a distributor housing having an anchoring element fixed thereon in said engine, a distributor shaft within said housing and driven by said engine, a pointer fixed on said housing, means for fixing said anchoring element to said engine, and means for angularly adjusting said housing in said anchoring element.

3. In an internal combustion engine, a distributor housing having an anchoring element fixed thereon, a distributor shaft 60 within said housing and driven by said engine, a non-rotatable connection between said anchoring element and engine capable of limited longitudinal movement, and means for angularly adjusting said housing 65 in said anchoring element.

4. In an internal combustion engine, a distributor housing having an anchoring element fixed thereon mounted in said engine, a distributor shaft mounted in said housing and driven by said engine, means 70 for fixing said anchoring element to said engine, an indicator mounted on said housing and registering on a dial on said anchoring element, and means for angularly adjusting said housing in said anchoring element.

5. In an internal combustion engine, a distributor housing mounted thereon and provided with an anchoring plate fixed thereto, a distributor shaft within said housing and driven by said engine, a pointer on said housing comprising a plate abutting said anchoring plate and slideable angularly relatively thereto, a non-rotatable connection between said anchoring plate and housing 85 permitting limited relative longitudinal movement, and means for angularly adjusting said housing in said anchoring plate.

6. Mounting means for a shaft comprising a casting having an aperture therein, a 90 housing fitting within said aperture, a shaft rotatably supported in the housing and held against axial movement relative thereto, an anchoring element fixed to said housing, and a non-rotatable connection between said 95 anchoring element and casting capable of limited axial movement.

7. Mounting means for a shaft comprising a casting having an aperture therein, a 100 housing fitting within said aperture, a shaft rotatably supported therein and held against axial movement relative thereto, an apertured anchoring plate fixed to said housing and extending in a plane perpendicular to 105 said shaft, and a connection between said plate and casting comprising a bolt extending through said plate and fixed in said casting and arranged to permit slight axial movement of said plate relative to the casting.

8. In a device of the class described, a support, a rotatable shaft, and a housing for the shaft normally held non-rotatable with respect to the support and capable of limited axial movement with respect thereto.

9. In a device of the class described, a support, a rotatable shaft, a housing for the shaft, and means secured to the housing and the support and so arranged as normally to prevent relative rotation of the housing and the support and allow limited axial movement of the housing with respect to the support.

10. In a device of the class described, a 125 support, a rotatable shaft, a housing for the shaft, and means clamped to the housing and loosely secured to the support so as normally to prevent relative rotation of the housing and the support and allow 130

limited axial movement of the housing with respect to the support.

11. In an internal combustion engine, a distributor which includes a shaft and a housing therefor, means normally to hold the housing non-rotatable with respect to the engine, a pointer carried by the housing, means for permitting rotation of the housing relative to the engine so as to vary the spark advance, and a scale on which the pointer indicates the spark advance.

12. In an internal combustion engine, a distributor which includes a shaft and a housing therefor, means secured to the engine and clamped around the housing so as normally to hold the housing non-rotatable with respect to the engine, a pointer carried by the housing, means whereby the clamp may be released in order to permit rotation of the housing with respect to the engine so as to vary the spark advance, and a scale on the first-mentioned means on which the pointer indicates the spark advance.

13. In an internal combustion engine, a driving shaft, a distributor on one side of the driving shaft, driven mechanism on the other side of the driving shaft, means secured to the distributor housing and the engine block and so arranged as normally to prevent rotation of the housing with respect to the block and to permit limited axial movement of the housing with respect to the block, a driving connection between the distributor shaft and the driving shaft, a third shaft, and a driving connection between the third shaft and the distributor shaft which allows relative axial movement of the two shafts without affecting the driving connection therebetween.

14. In an internal combustion engine, a driving shaft, a distributor on one side of the driving shaft, driven mechanism on the other side of the driving shaft, means secured to the engine block and clamped around the distributor housing so as normally to prevent rotation of the housing with respect to the engine block and to allow relative axial movement of the housing and the engine block, a driving connection between the distributor shaft and the driving shaft, a third shaft, a driving connection between the third shaft and the distributor shaft which allows relative axial movement of the two shafts without affecting the driving connection therebetween, a pointer carried by the housing, means whereby the clamp may be released so as to permit relative rotation of the housing and the shaft in order to vary the spark advance, and a scale on which the pointer indicates the spark advance.

15. The combination of an internal combustion engine, a distributor, and means to secure the distributor to the engine so as to hold the distributor non-rotatable with

respect to the engine and to allow a limited amount of axial movement of the distributor with respect to the engine.

16. In an internal combustion engine, a cylinder block, a driving shaft extending longitudinally of the cylinder block, a driven mechanism on each side of the cylinder block, and means for driving the driven mechanisms from the driving shaft including shafting extending transversely through the cylinder block.

In testimony whereof I affix my signature
HERMAN SCHWARZE.
